(57) **ABSTRACT**

A new and distinct *Sansevieria* plant having leaves with an intense yellow center area, delimited by a dark green border with some irregular grey tones.

1 Drawing Sheet

1

Botanical classification: *Sansevieria* sp.

Varietal denomination: 'OSV Sans 005'.

BACKGROUND OF THE INVENTION

The present invention comprises a new and distinct variety of *Sansevieria* plant, having the varietal name of 'OSV Sans 005' and commercially referred to as "Citrine Star". The new variety was discovered and selected by the breeder in a cultivated production bed environment in Williamsburg, Costa Rica as a naturally occurring mutation amongst a population of unpatented and unnamed *Sansevieria* plants. As such, the exact parentage is unknown. The new variety was selected and first asexually reproduced by rhizome cuttings in Williamsburg, Costa Rica. 'OSV Sans 005' has been trial and field tested and has been found to retain its distinctive characteristics and remain true to type through successive propagations. The present invention has not been evaluated under all possible environmental conditions. The phenotype may vary with variations in environment without a change in the genotype of the plant.

When compared to *Sansevieria* variety named 'OSV Sans 002' (U.S. Plant patent application Ser. No. 17/495,392), the new variety exhibits a similar rosette leaf formation with leaves growing upward and having an arch of approximately 60°. However, 'OSV Sans 005' has a large, yellow colored center area with grey-green and green colorations along the margin, while 'OSV Sans 002' has a grey-green colored center strip with vertical, yellow colored strips adjacent

2

thereto. Further, the following characteristics distinguish 'OSV Sans 005' from other *Sansevieria* varieties known to the breeder:

- 5 Rosette leaf formation;
Leaves grow mostly upward; and
Large, yellow vertical line along center of the leaves.

DESCRIPTION OF THE DRAWING

The accompanying photographic drawing taken at 10 approximately 18 weeks of age illustrates the new variety, with the colors being as nearly true as is possible with color illustrations of this type.

DESCRIPTION OF THE PLANT

15 The following detailed description sets forth the characteristics of the new variety at approximately 2 years of age. The data which defines these characteristics was collected in a greenhouse in September of 2021 in Winter Garden, Fla. Plants of the new variety were grown under 2,000 foot candles of artificial light in 15 cm pots in a climate-controlled greenhouse in Winter Garden, Fla. having 86% relative humidity and an average temperature of 28° C. Color references are primarily to the Munsell Plant Tissue Color Book, 2019 publication, except where general color terms are used.

PLANT

Time to initiate roots: About 12 days at an average of 23° C. night temperatures and 30° C. day temperatures.

Time to develop roots: About 21 days at an average of 23° C. night temperatures and 30° C. day temperatures.
 Time to produce a finished plant from a rooted cutting: About 8 weeks in a 15 cm container.
 Rooting habit and description: Hair-like roots spread out and wrap at the base. 5
 Form: Spreading.
 Height from media surface to top of foliage: 14.0 cm.
 Plant diameter: 21.6 cm.
 Plant shape: Rosette, having a circular arrangement of the leaves. 10
 Vigor: Strong.
 Strength: Rigid, with no need for artificial support.
 Disease resistance/susceptibility: Nothing specific noted to date. 15
 Pest resistance/susceptibility: Resistant to thrips and aphids.
 Temperature tolerance: Sensitive to temperatures below 7° C. or above 38° C.
 Drought tolerance: Very tolerant due to the ability of the leaves to retain water. 20
 Flowers: None observed to date.
 Seeds/fruit: None present.
 Stem:
 Length.—1.3 cm.
 Diameter.—2.0 cm. 25
 Shape.—Vertical column.
 Color.—5Y 8/2.
 Texture.—Coriaceous and glabrous.
 Strength.—Sturdy and rigid.
 Internode length.—Not applicable.
 Leaves:
 Arrangement.—Basal rosette.
 Average number per plant.—17.
 Length.—12.1 cm.
 Width.—6.4 cm.
 Shape of leaf (generally).—Gladiate. 30
 Shape of apex.—Apiculate.

Shape of base.—Cuneate.
 Margin description.—Entire.
 Aspect.—Mostly erect, arching outwardly to about 60°.
 Texture and luster.—Upper surface: Coriaceous and glabrous. Lower surface: Coriaceous and glabrous.
 Pubescence.—Upper surface: None present. Lower surface: None present.
 Fragrance.—None present.
 Color.—Young leaves: Upper surface: Majority of leaf is a 5Y 8/8 and 2.5GY 6/4 central line that fades into 2.5GY 7/6; margins are speckled with 7.5GY 5/6 and 7.5GY 3/2. Lower surface: Majority of leaf is speckled with 5Y 8/6 and 5Y 8/4; margins are mostly 5GY 5/6 speckled with 7.5GY 3/2; streaks of 7.5GY 6/2 that fade into 7.5GY 7/4 are present. Mature leaves: Upper surface: Majority of leaf is a 5Y 8/8 and 2.5GY 6/4 central line that fades into 2.5GY 7/6; margins are speckled with 7.5GY 5/6 and 7.5GY 3/2. Lower surface: Majority of leaf is 5Y 8/8 that fades into 5Y 8/6 and 5Y 8/4; margins are mostly 5GY 5/6 speckled with 7.5GY 3/2; streaks of 7.5GY 6/2 that fade into 7.5GY 7/4 are present. 10
 Veins.—Venation pattern: Parallel. Color: Upper surface: 2.5GY 6/4 central line that fades into 2.5GY 7/6; 5Y 8/8 surrounds the central line. Lower surface: Streaks of 7.5GY 6/2 that fade into 7.5GY 7/4 present; 5Y 8/8 that fades into 5Y 8/6 surrounds the streaks. 15
 Sheath:
 Length.—1.9 cm.
 Width.—3.8 cm.
 Color.—2.5GY 8/2.
 Texture.—Coriaceous and glabrous.
 I claim:
 1. A new and distinct variety of *Sansevieria* plant named 'OSV Sans 005', as is herein illustrated and described. 20
